UNITED STATES PATENT OFFICE.

ROLAND C. MITCHELL, OF OAKLAND, CALIFORNIA.

PORTABLE CLAMP-SOCKET.

1,360,133.

Specification of Letters Patent. Patented Nov. 23, 1920.

Application filed February 15, 1918. Serial No. 217,393.

To all whom it may concern:

Be it known that I, ROLAND C. MITCHELL, a citizen of the United States, residing at Oakland, in the county of Alameda and State of California, have invented certain new and useful Improvements in Portable Clamp-Sockets, of which the following is a specification.

This invention relates to new and useful improvements in portable clamp sockets, and the primary object of the invention is to provide a very efficient and durable clamp socket of this character which is especially adapted for application on deck cables used in mining, trench, and tunnel work. This socket is formed of indestructible waterproof material, and may be easily applied to or removed from the cable with very little trouble.

Another and equally important object of the invention is to provide an electrical fixture of the character mentioned, which, by reason of its peculiar shape, can be advantageously used in the wiring of trenches, tunnels, and the like for illumination; said fixture being of a shape that will permit the pulling of the same over and through such obstructions as may be encountered during the stringing of the line wires through a trench, tunnel, or the like, without the liability of catching in said obstructions, and in this way rendering the "stringing" operations difficult and lengthy.

Another object of the invention is to provide a device of this character which is easily and simply constructed, inexpensive to manufacture, and one which will be very efficient in operation.

With these and numerous other objects in view, my invention consists of the novel features of construction, combination, and arrangement of parts which will be herein referred to and more particularly pointed out in the specification and claim.

In the accompanying drawings:

Figure 1 is a perspective view of the device with the parts assembled,

Fig. 2 is a plan view with the clamping plate removed, and

Fig. 3 is a transverse section through the socket.

In describing my invention, I shall refer to the drawings in which similar reference characters designate corresponding parts throughout the several views. The numeral 1 designates the base plate of my new and

improved portable socket, said plate being elongated or substantially rectangular in shape and having its opposite ends tapered and its opposite marginal portions flattened as at 1' as shown in the accompanying drawings. The plate has connected therewith on its upper side a hanging loop 2 to permit the same to be readily secured in position on the wall of the tunnel or trench, or support against which the cable is strung.

The front face of the base plate 1, is provided with a centrally disposed enlarged chamber 3 therein, which is countersunk, and said chamber has grooves 4 connecting diametrically opposite points thereof with the opposite ends of the plate. These grooves 4, are adapted to receive the cable 5 which is of the conventional type ordinarily employed in tunnels, mines, etc., and the said cable has a pair of conductor wires 6 and 7, which are positioned within the enlarged chamber 3. The outer covering is removed from the cable adjacent the chamber, and the conductor wires are spread apart as clearly shown in Fig. 2 of the drawings.

Positioned within the chamber 1 are terminals 8 and 9, the terminal 9 being of the conventional form, substantially yoke-shaped, having a binding post 10, and an upwardly extending spring contact finger 11 that is adapted for engagement with a lamp. The other terminal 8 is provided with a binding post 12, and an extending portion 13 that is secured into engagement with a curved spring contact finger 14 that is adapted to normally engage the center portion of the lamp plug when the lamp is in position as will be hereinafter more fully described.

The cable 5 and its adjacent open portion is secured in position on the plate 1, by means of an outer clamping plate 15, corresponding in shape and size to the base 1 and having its opposite marginal portions flattened as at 15' said plate having a centrally disposed aperture 16 therethrough adapted for alinement with the chamber 3 in the plate 1. The opening is preferably provided with an internally threaded lining 17 having a projecting lip 18 thereon, that is adapted for engagement with the spring contact finger 11 when a lamp 19 is positioned through the opening as clearly shown in Fig. 3 of the drawings.

The two plates, namely, the base plate 1

and the clamping plate 15, are adapted to be connected together by a pair of fastening bolts 20 that extend through alining openings in said plates, and which have 5 their inner ends positioned in countersunk nuts 21 in the plate 1. By this means, the plate 15 may be detachably positioned on the base plate 1, to securely hold the cable in position, and the opening through said 10 clamping plate permits the incandescent lamp 19 to be positioned in the socket. To render the connection between the base 1 and the clamping plate 15 fluid tight a rib 25 is formed on the inner side of the base at 15 a point in proximity to the marginal portions thereof, and is adapted to be received in a complementally formed groove in the adjacent side of said clamping plate 15; it of course being understood in this connection that suitable forms of packing, if desired, can be arranged in the groove to insure fluid tight connection between the same and said rib.

The operation of this type of socket is 25 easily understood, and it is obvious that with very little trouble, the socket may be applied at any point on the deck cable. When the lamp is in position through the clamping plate, the spring finger 11 will 30 engage the projecting lip on the metal lining 17 that receives the plug of said lamp, while the center spring contact 14 will engage the bottom of the plug, thereby completing the circuit so that the lamp will light. This 35 device is formed of indestructible waterproof material of any desired kind, so that it will not break when the cable is moved from place to place. There is a small groove for a waterproof gasket at the top of the 40 plate around the outer edge, and a small ridge is placed at each end of the socket so no water can enter around the cable.

By reason of the peculiar shape of the base 1 and the clamping plate 15, it will be 45 readily understood that the fixture is rendered especially useful in the wiring of

trenches, tunnels, and the like, for illumination, since the lines or wires can be pulled or drawn through or over the ground or other object without liability of catching in debris, projections, or similar obstructions, the tapered ends of said base and clamping plate serving to permit wedging of the fixtures therethrough while the flattened marginal portions afford efficient skid surfaces. 55 Since, as a general rule, wiring of the nature above stated is but of a temporary kind, it will be appreciated that my novel fixture is especially advantageous for use in this work.

From the foregoing description of the 60 construction, and operation of my new and improved device, the manner of applying the same to use and its operation will be readily understood, and it will be seen that I have provided a simple and efficient device, 65 and while I have shown and described the device as embodying a specific structure, I desire that it be understood that such changes may be made in said structure as do not depart from the spirit and scope of the 70 invention as claimed.

Having fully described my invention, what I claim as new, and desire to secure by Letters Patent, is:

The combination with a two part insulator casing constructed and arranged to form a chamber, of spaced screws carried in one part of said casing at one side of the chamber, a contact shell in the other part of the casing, conductor wires engaged with the screws, a substantially Y-shaped member connected to one of the screws, a curved leaf spring finger on one limb of the Y-shaped member and engaged with the shell, a substantially U-shaped resilient terminal fixed at one end between the screws, and a connection between the other screw and said fixed end of the terminal. 75 80 85

In testimony whereof I affix my signature hereto.

ROLAND C. MITCHELL.
